Inventor

Frank M. Correa

UNITED STATES PATENT OFFICE

FRANK M. CORREA, OF HONOLULU, TERRITORY OF HAWAII

BEDDING CLAMP

Application filed December 12, 1928. Serial No. 325,566.

This invention relates to improvements in a bedding clamp, and has for its object to provide a simple, inexpensive and easily operated means whereby bed clothes may be held 5 in place.

A further object of this invention is to provide in a bedding clamp, a fixed jaw having a shank, and a movable jaw slidable on the shank, and a self-locking connection 10 therewith.

A still further object of this invention is to provide a very simple and inexpensive means whereby bed clothing may be securely held in place over infants or others sleeping 15 in the bed.

With the above and such other objects in view as may be more fully hereinafter described, I have invented the device illustrated in the accompanying drawings, in which:

20 Figure 1 is a side elevational view of my invention shown in operation.

Figure 2 is a perspective view of the device removed from the bedding.

25 Figure 3 is an end view thereof, a wall of a slide member being broken away.

Figure 4 is a detail perspective view of a clamp lock.

Like reference characters indicate like 30 parts throughout the specifications and in the several views of the drawings, in which 1 indicates a mattress, the cover 2 of which is held fixed thereto at its bottom and side edges by means of a bedding clamp 3, said clamp consisting of a corrugated upper jaw

35 4 terminating in an integral vertical shank 5 having an elongated slot 6 therein and a toothed edge 7, the upper surface 8 of the teeth being horizontal and the side walls 9 thereof being inclined, whereby the inclined

40 surface 10 of the dog 11 may slide upwardly over said teeth 7, but will be pressed into engagement by the spring 12, carried on the rear wall 13 thereof, with the horizontal surface of said teeth, in order that when the

45 member 4 on the shank 5 is raised thereon, its movement cannot retract until the finger piece 15 of the lever 16 pivoted at 17 to the walls of the member 14, is pressed to force

50 the dog 11 against the tension of spring 12 out of engagement with said teeth. Integral-

ly formed on the slide 14 is a jaw 18 similar to jaw 4 in form.

From the above description it will be seen that it is only necessary to place the jaw member 4 upon the upper surface of the bed clothing on the mattress letting the shank 5 rest against the edge 19 of the mattress, and project the jaw 18 under the mattress, then by pushing the jaw 18 toward the jaw 4 the member 14 will slide up the shank 5 and automatically lock itself, whereby the bed clothing and mattress will be securely clamped together; the corrugations of the jaws taking a firm hold of said bedding and preventing possibility of the clamp slipping from engagement therewith. Thus the bed clothing will be securely held to the mattress whereby children or other persons will not be able to kick the cover from over them.

Having now described my invention, that 70 which I claim to be new and desire to protect by Letters Patent, is:

1. A device of the character described comprising a shank terminating in a fixed jaw, at its upper end, said shank being bifurcated 75 and having a toothed inner portion, a slidable jaw, a relatively short socket by which said jaw is carried said socket being slidable upon said shank, and a pawl pivoted within said socket member and operable within said bifurcation and upon said teeth, said pawl having an extension end terminating in a head projecting above said socket.

2. A device of the character described comprising a shank terminating in a fixed jaw, 85 at its upper end, said shank being bifurcated and having a toothed inner portion, a slidable jaw, a relatively short socket by which said jaw is carried said socket being slidable upon said shank, and a pawl pivoted within said socket member and operable within said bifurcation and upon said teeth, said pawl having an extension end terminating in a head projecting above said socket, both of said 90 jaws being corrugated.

In testimony whereof I affix my signature.
FRANK M. CORREA.
